SCREW LIFT ELEVATOR FOR GRAIN OR THE LIKE

James R. Nolan, Fort Worth, Tex., assignor to Fort Worth Steel and Machinery Company, Fort Worth, Tex., a corporation of Texas

Filed July 15, 1958, Ser. No. 51,802

Term of patent 14 years

(Cl. D41—1)

Figure 1 is a front elevational view of a screw lift elevator for grain or the like embodying my new design;
Figure 2 is a side elevational view of the elevator shown in Figure 1; and

Figure 3 is a fragmentary perspective view, taken from the right in Figure 1, of the lower portion of the article.

The design for the screw lift elevator for grain or the like shown in the drawing is characterized by the hopper near the bottom of the elevator, and the power transmission units at the top and bottom of the elevator, having the configurations shown.

I claim:

The ornamental design for a screw lift elevator for grain or the like, substantially as shown and described.
